DESIGN FOR A SCALP MASSAGER

Jewel K. Kahn, Hastings, Nebr., assignor to Raymond W. Kerr and Charlotte J. Kerr, copartners, doing business as R. W. Kerr Co., Hastings, Nebr.

Application November 1, 1945, Serial No. 123,386

Term of patent 14 years

(Cl. D83—1)

To all whom it may concern:

Be it known that I, Jewel K. Kahn, a citizen of the United States, residing at Hastings, in the county of Adams and State of Nebraska, have invented a new, original, and ornamental Design for a Scalp Massager, of which the following is a specification, reference being had to the accompanying drawing, forming a part thereof.

Fig. 1 is a side elevation of a scalp massager embodying my new design.

Fig. 2 is also a side elevation of the scalp massager shown in Fig. 1 but with same turned through ninety degrees as compared to Fig. 1.

Figs. 3 and 4 are, respectively, bottom and top views of the scalp massager shown in Fig. 1.

Fig. 5 is a transverse sectional view taken substantially along the line 5—5 in Fig. 2.

I claim:

The ornamental design for a scalp massager, substantially as shown.

JEWEL K. KAHN.
